US0D1104686S

(12) **United States Design Patent** (10) Patent No.: **US D1,104,686 S**
(45) Date of Patent: ** Dec. 9, 2025

(54) **SCISSORS**

(71) Applicant: **Huan Zhang**, Jiangsu (CN)

(72) Inventor: **Huan Zhang**, Jiangsu (CN)

(**) Term: **15 Years**

(21) Appl. No.: **35/522,796**

(22) Filed: **Sep. 23, 2024**

(80) **Hague Agreement Data**

Int. Filing Date: **Sep. 23, 2024**

Int. Reg. No.: **DM/241315**

Int. Reg. Date: **Sep. 23, 2024**

Int. Reg. Pub. Date: **Nov. 1, 2024**

(51) LOC (15) Cl. **08-03**

(52) U.S. Cl.

USPC **D8/57**

(58) **Field of Classification Search**

USPC D8/52-58; D28/54, 56, 57

CPC B26B 13/20; A45D 29/18

See application file for complete search history.
